DESIGN FOR A LADY'S POLONAISE.

SPECIFICATION forming part of Design No. 18,017, dated January 10, 1888.

Application filed December 9, 1887. Serial No. 257,468. Term of patent 9 $\frac{1}{2}$ years.

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 18,017, dated January 10, 1888.

Application filed December 9, 1887. Serial No. 257,468. Term of patent 3½ years.

To all whom it may concern:

Be it known that I, MARY TURNER, of the city, county, and State of New York, have invented and produced a new and original Design for a Pattern of a Lady's Polonaise; and I do hereby declare that the engraved prints accompanying this specification convey to any one accustomed to using paper patterns a clear understanding of how a garment made up by the pattern will appear.

The design shows long close-fitting fronts that display a group of draping plaits in their back edges and a diagonal closing above the waist-line, below which they flare in V shape to reveal the skirt; under-arm gores falling

with the effect of large pocket-laps upon the fronts; a long close-fitting back that exhibits underfolded plaits at the end of the side back seams and a bouffant draping of loops at the center seam, a standing collar, and coat sleeves. 20

What I claim as my invention, and desire to secure by Letters Patent, is—

The design for a lady's polonaise, as shown in the engraved prints accompanying this specification.

MARY TURNER.
